UNITED STATES PATENT OFFICE

JOHN DILLON, OF HOUSTON, TEXAS.

LEVER-JACK.

No. 907,226.

Specification of Letters Patent. Patented Dec. 22, 1908.

Application filed February 17, 1908. Serial No. 416,244.

To all whom it may concern:

Be it known that I, JOHN DILLON, a citizen of the United States, and resident of Houston, in the county of Harris and State 5 of Texas, have invented certain new and useful Improvements in Lever-Jacks; and I do hereby declare that the following is a full, clear, and exact description thereof.

The invention relates to a species of lever-jacks each comprising a lever, a pair of pawls in connection with the lever, a rack-edge slide-bar with which the pawls co-operate, a yielding spring-controlled pawl-tripper, and means for adjusting the tripper 10 with reference to determining the direction of movement of said bar when said lever is actuated; the object of said invention being to provide simple, economical and efficient implements of the species aforesaid, which 15 20 25 30 35 40 45 50 55 60 65 70 75 80 85 90 95 100 105 110

object is attained by the general construction, arrangement and co-operation of parts in the improved jacks, one of the same being hereinafter particularly set forth with reference to the accompanying drawings, especial attention being called to its pawl-tripper reciprocative in the plane of the power applied thereto by the pawls, to thus obviate binding of said tripper and to insure the full efficiency of its controlling spring with respect to retracting said pawls from the rack-edge of the slide-bar at proper times. Attention is also called to a shifting-cam of the implement mounted in connection with the pawl-tripper.

Figure 1 of the drawings represents a side elevation of an improved lever-jack having the frame or stand thereof partly broken away, a detachable plate portion of the same being removed; Fig. 2, a side elevation of a fragment of the jack; Fig. 3, a diagram illustrating movement of various parts in said jack when the pawl-tripper of same is adjusted to provide for step-by-step reverse travel of the slide-bar incidental to operations of the lever, and Fig. 4, a vertical section view of a fragment of the jack, this view being indicated by lines 4-4 in Fig. 1.

Referring by letter to the drawings, A indicates the jack-frame or stand, the same being of any suitable design, B the slide-bar of the jack, b a stop-screw engaging a side groove in said bar, C the jack-lever fulcrumed in said frame, D, E, the pawls in connection with said lever to engage a rack-edge of said bar, and c, d, suitably arranged springs by which the proper en-

gagement of said pawls with the aforesaid bar is insured; the general construction and arrangement of the parts thus far described being common in the art and susceptible to various changes in matters of detail from what is herein shown.

At one end, the jack-frame is provided with a chamber e containing a spiral-spring F surrounding a cylindrical shank-end of the longitudinally reciprocative pawl-tripper element G of the jack, this shank being guided in an aperture in a partition f dividing said chamber from the main chamber of said frame. The spring F is confined between the partition f and a washer g held on the shank-end of the tripper by a set-screw h, and an annular shoulder i of the tripper opposes the partition f within the main chamber of the jack-frame. The other end of the tripper is in the form of a hook having a preferably inclined terminal j that is at times in the path of a lateral lug k of the pawl D, and an inclined shoulder m of said tripper is at times in the path of a lateral lug n of the pawl E, said pawls, the fulcrum p for the lever C and the pawl-controlling springs being with the major portion of the aforesaid tripper in the main chamber of the jack-frame. It is preferable, as herein shown, to have the hook-end of the tripper in sliding contact with the flange of the guide-way for the slide-arm of the jack.

To facilitate access to the aforesaid chambers of the jack-frame, these chambers are closed on one side by a detachable plate H, one end of which is herein shown as having a flange r that caps an end of said chamber e, said plate being secured in place by screws s and provided with a longitudinal slot t and an outer lug u. Extending through the plate-slot and engaging a boss v of the tripper is a screw w constituting a pivot for a cam I opposing the plate-lug u and provided with wings x to facilitate its adjustment.

When the cam I is in the position shown in Fig. 2, the tripper G is adjusted to have the inclines j, m, thereof in the paths of the lugs k, n, of the pawls D, E, the jack being then operative for a step-by-step recession of its slide-bar, incidental to oscillation of its lever.

Assuming the movable parts to be in the position shown in Figs. 1 and 2, an upward movement of the jack-lever C will cause a recession of the bar B and the pawl D, but in the meantime the pawl E will automati-

ically engage with one of the teeth of said bar and the load will be quickly distributed on both of said pawls. During the recession of the pawl D, its lug *k* will make contact 5 with the incline *j* of the tripper G, whereby this tripper is moved in the direction to store power in the spring F with which it is engaged. A continued upward movement of the jack-lever C will slightly raise the bar 10 B, by means of the pawl E releasing the load from the pawl D, and the power previously stored in the spring F will then operate, through the inclines of the tripper G, against the lug *k* on the pawl D to remove this pawl 15 from contact with said bar. Now when the jack-lever C is moved downward, the bar B is caused to recede, at the same time raising the pawl D, and the lug *n* of the pawl E coming into contact with the inclined lug *m* 20 of the tripper G, the latter is again moved in the direction necessary to store power in its spring F during continued downward movement of said lever. The pawl D being free of the tripper, it automatically engages 25 with the teeth of the bar B, and during the downward movement of the jack-lever, said pawl is caused to slightly raise said bar, thus relieving the load from the pawl E, the result being that the power stored in the spring 30 F actuates said tripper to remove said pawl E from contact with the aforesaid bar. A continuance of the operations described will result in a lowering of the bar B step-by-step, the distance of one half a notch of its 35 rack-edge being accomplished at each stroke of the jack-lever.

The pawl-tripper being reciprocative in the plane of the power applied thereto by the pawls to intermittently move it in one 40 direction against resistance of its controlling spring, there is no liability of said tripper to bind in or on its guides, and the efficiency of its controlling spring is not in the least impaired.

45 When step-by-step outward movement of the slide-bar is desirable, as a result of manipulation of the jack-lever, the cam I is turned on its pivot to have its greatest radius in line with the opposing stationary lug *u*, and thus the pawl-tripper is adjusted to 50 move the same inward out of the paths of the opposing lugs of the pawls, said pivot being in connection with said tripper and slidable in the longitudinal slot *t* of the de- 55 tachable plate H of the jack-frame. This adjustment of the tripper having been effected, the pawls are both in engagement with the rack-edge of the slide-bar and operate alternately to effect the step-by-step out- 60 ward movement of said bar, incidental to oscillation of the jack-lever.

I claim:

1. In a jack, the combination of a frame, a rack-edge slide-bar guided in the frame, a 65 lever having its fulcrum in said frame, a

pair of pawls carried by the lever to be engageable with said edge of the slide-bar, a spring-controlled longitudinally reciprocative pawl-tripper guided in the aforesaid frame, and lugs extending laterally from 70 the pawls in position to intermittently actuate the tripper for a time against resistance of its spring, the reciprocation of said tripper being in the plane of the power applied thereto by said pawls. 75

2. In a jack, the combination of a frame, a rack-edge slide-bar guided in the frame, a lever having its fulcrum in said frame, a pair of pawls carried by the lever to be engageable with said edge of the slide-bar, a 80 spring-controlled longitudinally reciprocative pawl-tripper guided in the aforesaid frame, means for holding the same out of working position, and lugs extending laterally from the pawls to intermittently actuate 85 the tripper for a time against resistance of its spring when said tripper is in working position, the reciprocation of this tripper being in the plane of the power applied thereto by said pawls. 90

3. In a jack, the combination of a frame, a rack-edge slide-bar guided in the frame, a lever having its fulcrum in said frame, a pair of pawls carried by the lever to be engageable with said edge of the slide-bar, a 95 guide, a tripper having a shank-end engaging the guide, an inclined shoulder and a hook-end; a tripper-supporting spring opposing said guide, and lugs extending laterally from the pawls to have intermittent 100 alternate moving contact for a time with the hook-terminal and shoulder of the tripper against resistance of the spring, said tripper being reciprocative in the plane of the power applied thereto by said pawls. 105

4. In a jack, the combination of a frame, a rack-edge slide-bar guided in the frame, a lever having its fulcrum in said frame, a pair of pawls carried by the lever to be engageable with said edge of the slide-bar, a 110 spring-controlled yielding pawl-tripper, a cam on a pivot in connection with the tripper and opposite a stationary portion of the aforesaid frame to shift said tripper in and out of working position; and lugs extending laterally from the pawls to intermittently actuate the tripper for a time against resistance of said spring when this tripper is in working position to have reciprocation in the plane of the power applied thereto by 115 said pawls. 120

5. In a jack, the combination of a frame, a rack-edge slide-bar guided in the frame, a lever having its fulcrum in said frame, a pair of pawls carried by the lever to be engageable with said edge of the slide-bar, a 125 guide, a tripper having a shank-end engaging the guide, an inclined shoulder and a hook-end; a tripper-supporting spring opposing said guide, lugs extending laterally 130

from the pawls to have intermittent alternate moving contact for a time with the hook-terminal and shoulder of the tripper against resistance of its spring when said 5 tripper is in working position, it being then reciprocative in the plane of the power applied thereto by the pawls; and a cam on a pivot in connection with the aforesaid tripper and opposite a stationary portion of the 10 aforesaid frame, said cam being operative to

shift the tripper in and out of working position.

In testimony that I claim the foregoing I have hereunto set my hand at Houston in the county of Harris and State of Texas in 15 the presence of two witnesses.
